DESIGN FOR A CABINET TOP PANEL

Perry F. Alsfelder, Cincinnati, Ohio, assignor to
The Brunhoff Manufacturing Company, Cincinnati,
Ohio, a corporation of Ohio

Application June 13, 1940, Serial No. 92,981

Term of patent 3½ years

To all whom it may concern:

Be it known that I, Perry F. Alsfelder, a citizen of the United States, residing at Cincinnati, in the county of Hamilton and State of Ohio, have invented a new, original, and ornamental Design for a Cabinet Top Panel, of which the following is a specification, reference being had to the accompanying drawing, forming part thereof.

the cabinet top panel of my new design in full lines. A cabinet is shown in dot-and-dash lines for illustrative purposes only.

I claim:

The ornamental design for a cabinet top panel, as shown and described.

PERRY F. ALSEFELDER.
